UNITED STATES PATENT OFFICE.

JOHN P. MURPHY, OF CHARLESTON, SOUTH CAROLINA.

SLIDE FEED-VALVE.

1,166,242.

Specification of Letters Patent. Patented Dec. 28, 1915.

Application filed February 9, 1915. Serial No. 7,028.

To all whom it may concern:

Be it known that I, JOHN P. MURPHY, a citizen of the United States, residing at Charleston, in the county of Charleston and State of South Carolina, have invented certain new and useful Improvements in Slide Feed-Valves; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a slide feed valve for railroad air-brake systems and has for its object to provide a valve which will remain tight under service conditions, so that the proper operative pressure can be maintained.

For a complete understanding of this valve it will be stated that the pressure lead to the valve is maintained at 90 lbs. and it is required for proper operation that the pressure passing from the valve be maintained at 70 lbs. Under the influence of pressure the valves as heretofore constructed quickly become worn to such an extent that the pressure from the valve rises above the proper effective pressure, and at times to such an extent that the pressure lead to the valve and from the valve becomes balanced at 90 lbs., which seriously interferes with and hampers the proper action of the air-brake system. In order to obviate and prevent this leakage of pressure so that the pressure from the valve will not exceed the effective working pressure of 70 lbs. and to insure a strong and serviceable construction I have made this present invention, which consists in the novel construction of the slide valve, so that the slide will not only be maintained in a tight and serviceable condition when first applied, but will remain in a tight and serviceable condition under influences of wear, so that the necessity of renewal of the slide becomes practically eliminated.

The invention also consists in certain details of construction of the slide valve, all of which will be first fully described and afterward specifically pointed out in the appended claims.

Referring to the accompanying drawings, Figure 1 is a vertical transverse sectional

view through a slide feed valve constructed in accordance with this invention. Fig. 2 is a vertical longitudinal sectional view through the same. Fig. 3 is a vertical transverse sectional view through the slide valve taken on line 3—3 of Fig. 4, and Fig. 4 is a vertical longitudinal sectional view through the slide valve and piston taken on line 4—4 of Fig. 3.

Like numerals of reference indicate the same parts throughout the several figures, in which—

1 indicates the casing of the slide feed valve which is provided with a flange 2 for proper attachment by means of bolts or fastenings passed through the openings 3 in the flange 2. Entering the flange 2 is the pressure feed port 4 communicating with the port 5 in the bushing 6, which receives the slide valve, said bushing 6 being provided longitudinally thereof with a smooth flat channel 7 and in said channel near the inner end thereof with a transversely elongated port 8, which is in communication with the port or passage 9 which leads the pressure from the valve out of the flange 2 in the manner as shown in Fig. 1. Communicating with the port or passage 9 is a vertical port or passage 10 opening at 11 behind a diaphragm 12, which diaphragm is commanded by a spring-adjusting device 13 for regulating the tension of the diaphragm. Arranged behind the diaphragm 12 is a valve 14 having a stem 15 passing freely through a port 16 and in engagement with the face of the diaphragm 12, the valve 14 being resiliently held in position by means of the spring 17.

The chamber 18 within which the valve 14 is housed is provided with a port 19, which communicates with the passage 20 shown in dotted lines in Fig. 1 and in dotted and in full lines in Fig. 2, which passage 20 communicates with a port 21 entering the chamber 22 within which chamber the piston 23 operates.

Referring now to Fig. 4 it will be seen that the piston 23 is provided with a stem 24 which carries the slide 25 in the following manner. The stem 24 which enters the bushing or lining 6 of the valve is provided transversely thereof with an opening or perforation 26, while the slide 25 is bifurcated in the manner as shown in Fig. 3, so that the arms or walls 27 straddle the stem 24 and is guided thereby. The bottom por-

- tion 28 of the slide 25 being flat is ground into the longitudinal channel 7 in the bushing or lining 6 in the manner as shown in Figs. 3 and 4. Arranged in the perforation 5 or opening 26 in the stem 24 is a spiral spring 29 having its lower end normally bearing upon the lower portion of the slide 25 and within said spiral spring 29 is a pin or plunger 30 having preferably a rounded 10 head 31 for engagement with the bushing or lining 6 of the valve, the parts being arranged in the manner as shown in Figs. 3 and 4 so that when in assembled position a resilient yielding pressure is applied to the 15 slide 25 at the bottom portion thereof to hold the said slide in close and intimate engagement with its channel 7 in the bushing or lining 6, while a mutilated guide disk 32 as shown in elevation in Fig. 1 is formed 20 on the stem 24 for sliding engagement with the bushing or lining 6 to prevent cocking of the valve.

Having thus described the several parts of this invention its operation is as follows: 25 Pressure being led to the device through the feed port 4, the same passes into the bushing or lining 6 through the port 5 and acts behind the piston 23 to move said piston and slide valve away from the said port 5, this 30 movement causing the slide 25 to wholly or partially uncover the port 8 which is commanded by the slide 25. As said port is uncovered by the slide 25 pressure passes into the passage 9 and out of the device in 35 the manner as shown in Fig. 1, while the pressure passing into the passage 9 is also led into the vertical passage 10 and out of the port 11 behind the diaphragm 12 and through the passage 15 past the valve 14 and 40 into the chamber 18, whence it passes out of the port 19 into the passage 20 shown in dotted lines in Fig. 1 and from the passage 20 through the port 21 (Fig. 2) into the chamber 22 which is in front of the piston 45 23, thus acting against movement of the piston 23 toward the chamber 22 and tending to move said piston 23 and slide 25 in the direction of the port 8 to cover the same. It will therefore be seen that the extent of 50 movement of the slide 25 and consequent extent of opening of the port 8 depends upon the relative pressures on opposite sides of the piston 23, which relative pressure is regulated by the tension of the diaphragm 12 55 in the manner as heretofore described, so that by adjustment of said diaphragm the proper pressure can be caused to pass through the port 8 in the valve bushing or lining and out of the device by way of the 60 passage 9. Should however the slide 25 not be properly seated in its channel 7 or should by the construction of the slide 25 and its coöperating parts said slide become worn and incapable of its proper adjustment to its 65 wear, then the pressure entering the port 5

from the feed port 4 will leak past the slide 25 and enter the port 8 arranged to be commanded thereby and out from the device by way of the passage 9 irrespective of any proper longitudinal movement of the slide 70 25, thus rendering proper adjustment of pressure passing from the device impossible, and seriously interfering with the action of the air-brake system.

I lay no claim to a bifurcated slide having 75 a transverse pin for supporting and holding a leaf spring in engagement with the casing to maintain the slide in operative position.

Having thus fully described the invention it is apparent that the construction 80 shown in the accompanying drawings is susceptible to immaterial changes and I consider myself clearly entitled to all such changes and modifications as fall within the limit and scope of the appended claims.

What I claim as new and desire to secure by Letters Patent of the United States is—

1. A slide-feed-valve including a casing, a chamber therein, a valve including a piston and stem disposed in said chamber, said chamber being provided with a flat longitudinal channel, said casing being provided with a pressure supply port leading to said chamber on one side of said piston, the said chamber being provided with a port adjacent the first mentioned port, and provided with a pressure supply port on the other side of said piston, a bifurcated slide straddling the said valve stem and operable in said longitudinal channel in said casing to 100 cover the said port therein adjacent the first mentioned port, the said stem being provided with a transverse perforation, a headed pin arranged in said perforation and guided thereby and having its head in engagement with the wall of said chamber and a coil spring disposed on said pin in said perforation, said spring having one end in engagement with said slide and the other end in engagement with said pin to force the said 105 slide and pin oppositely to securely maintain the said slide in intimate contact with the flat bottom of said longitudinal channel.

2. A slide-feed-valve including a chamber provided with a longitudinal channel, a valve including a piston and stem in said chamber, said chamber being provided with ports, one of which enters the same in said longitudinal channel, a bifurcated slide mounted on said stem and operable in said longitudinal channel to close said port entering the same, the said stem being provided with a transverse perforation in line with said slide, a pin in said perforation and guided thereby and having its outer end in engagement with the wall of the said chamber, a spring disposed on said pin in said perforation and in engagement with said slide to force the said pin and slide in opposite directions to effectually maintain 115 120 125 130

the said slide in intimate contact with the bottom of said longitudinal channel.

3. A slide-feed-valve including a chamber having a longitudinal channel and a port 5 entering the said channel, a valve including a piston and a stem slideable within said chamber, a slide mounted on said stem and operable within said longitudinal channel to close said port, a pin disposed in said 0 stem and having one end in engagement with the wall of said chamber, a spring on

said pin in said stem and in engagement with said slide to effectually maintain the said slide in intimate contact with the bottom of said longitudinal channel.

15

In testimony whereof, I affix my signature, in presence of two witnesses.

JOHN P. MURPHY.
